UNITED STATES PATENT OFFICE

HOWIE BOGGS, OF POUND, VIRGINIA

CABLE REEL FOR MINING MACHINES

Application filed March 8, 1930. Serial No. 434,324.

The present invention relates to a cable reel for mining machines and has for its object to provide a structure for winding and unwinding electric conduits used in connection with electrically operating mining machinery remote from the car.

Another important object of the invention resides in the provision of a reel of this nature which is simple in its construction, inexpensive to manufacture, strong and durable, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is an end elevation of a mining machine showing the reel mounted in place,

Figure 2 is a top plan view thereof,

Figure 3 is a longitudinal section through the reel,

Figure 4 is a transverse section therethrough taken substantially on the line 4—4 of Figure 3,

Figure 5 is a sectional view taken substantially on the line 5—5 of Figure 3.

Referring to the drawings in detail it will be seen that from one end of the car or mining machine 5 there extends horizontally a U-shaped frame 6, on the sides of which are bearings 7 and 8, the latter being insulated from the frame as at 9 and electrically connected with the source of electrical energy by means of a lead 10.

Numeral 11 denotes a core of insulating material having bores 12 extending inwardly from the ends thereof and terminating equidistant from the center thereof. Disks 14 are mounted on reduced end portions of the core 11 and have cylindrical hubs 15 directed inwardly therefrom and anchored in place by means of screws or other fastening elements 16.

Trunnions 20 and 21 are formed on shanks 22 and 23 respectively which are formed with

longitudinally extending ribs 24 to be received in longitudinally extending grooves formed in the bores 12. The inner ends of the shanks are provided with openings for receiving bolts 25 to which the cables 26 are 55 engaged.

On the trunnions 21 there is keyed a pulley 27 operatively connected with an electric motor 28 in the machine or car 5 by means of a pulley 29 and belt 30. The cable 26 to the left of Figures 1 and 2, is grounded through the shank 24, the frame 6, etc., and may be used as a ground wire for the electric machinery while the other wire 26 to the right of these figures leads the current to the ma- 65 chinery.

It is thought that the construction, operation, utility and advantages of this invention will now be quite apparent to those skilled in this art without a more detailed description thereof. 70

The present embodiment of the invention has been disclosed in considerable detail merely for the purposes of exemplification since in actual practice it attains the features of 75 advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages. 80

Having thus described my invention, what 85 I claim as new is:

In a reel structure of the class described for electric cables, a core formed of non-conducting material and having reduced end portions, a pair of end disks having inwardly directed cylindrical collars at their centers fitting on the reduced portions, means for detachably connecting the collars to the reduced portions, said core being provided with a pair of inwardly directed bores from the 90 ends thereof terminating equi-distant from the center thereof, the walls of the bores being provided with a plurality of longitudinally extending grooves, trunnions having 95 shanks extending into the bores and formed 100

with longitudinally extending ribs to be received in the grooves, and bolts extending transversely partly through the core and the inner ends of the shanks having openings therein to receive the inner ends of the bolts, the outer end of each bolt projecting from the core for forming a terminal for a conductor.

In testimony whereof I affix my signature,
HOWIE BOGGS.
